UNITED STATES PATENT OFFICE

99,230

DESIGN FOR A LAMP

Evelyn Kathryn Wieland, Baltimore, Md.

Application January 28, 1936, Serial No. 60,848

Term of patent 14 years

To all whom it may concern:

Be it known that I, Evelyn Kathryn Wieland, a citizen of the United States, residing at Baltimore city and State of Maryland, have invented a new, original, and ornamental Design for Lamps, of which the following is a specification, reference being had to the accompanying drawing, forming part thereof.

I claim:—

The ornamental design for a lamp substantially as shown.

In testimony whereof I affix my signature.
EVELYN KATHRYN WIELAND.
